CLAIM

The ornamental design for a portable cervical traction device, as shown and described.

DESCRIPTION

FIG. 1 is a perspective view of a portable cervical traction device showing my new design;

FIG. 2 is second perspective view thereof;

FIG. 3 is third perspective view thereof;

FIG. 4 is fourth perspective view thereof;

FIG. 5 is fifth perspective view thereof;

FIG. 6 is a front view thereof;

FIG. 7 is a rear view thereof;

FIG. 8 is a left side view thereof;

FIG. 9 is a right side view thereof;

FIG. 10 is a top plan view thereof; and,

FIG. 11 is a bottom plan view thereof.

In the drawings, the broken lines show portions of a portable cervical traction device that form no part of the claim.
